US00D582299S

(12) **United States Design Patent**
Claypool

(10) **Patent No.:** **US D582,299 S**
(45) **Date of Patent:** **** Dec. 9, 2008**

(54) **THERMOMETER**

D269,600 S 7/1983 Mox
4,393,565 A 7/1983 Wilson et al.

(75) Inventor: **Christopher J. Claypool**, Huntersville, NC (US)

(73) Assignee: **Rubbermaid Incorporated**,
Huntersville, NC (US)

(Continued)

(**) Term: **14 Years**

(21) Appl. No.: **29/319,497**

(22) Filed: **Jun. 10, 2008**

OTHER PUBLICATIONS

Frank Edwards, Wristwatches - A Connoisseur's Guide, Nov. 18, 1997, 4 pages, A Firefly Book.

FIG. 1 is a perspective view showing my new design for a thermometer.

FIG. 2 is a front view of the thermometer shown in FIG. 1.

FIG. 3 is a left side view of the thermometer shown in FIG. 1, the right side view being a mirror image thereof.

FIG. 4 is a rear view of the thermometer shown in FIG. 1.

FIG. 5 is a top view of the thermometer shown in FIG. 1.

FIG. 6 is a bottom view of the thermometer shown in FIG. 1; and,

FIG. 7 is an exploded view of the thermometer shown in FIG. 1.

The dashed lines are for illustrative purposes only and form no part of my claimed design.
